FIG. 1 is a perspective view of a first embodiment of a seat frame showing my new design;

FIG. 2 is a right side elevation view thereof;

FIG. 3 is a left side elevation view thereof;

FIG. 4 is a top plan view thereof;

FIG. 5 is a front side elevation view thereof;

FIG. 6 is a perspective view of a second embodiment thereof;

FIG. 7 is a right side elevation view thereof;

FIG. 8 is a left side elevation view thereof;

FIG. 9 is a top plan view thereof;

FIG. 10 is a front side elevation view thereof;

FIG. 11 is a front side elevation view of a third embodiment thereof; and,

FIG. 12 is a front side elevation view of a fourth embodiment thereof.

The broken lines in the drawings represent environmental subject matter and form no part of the claimed design. The pairs of adjacently spaced jagged, broken portions indicate indeterminate length.
